UNITED STATES PATENT OFFICE

CHARLES K. WOODIN, OF BLOOMINGTON, ILLINOIS

DESIGN FOR A COMBINED WASHING MACHINE CASING AND WRINGER

Application filed June 22, 1931. Serial No. 40,289. Term of patent 7 years.

To all whom it may concern:

Be it known that I, CHARLES K. WOODIN, a citizen of the United States, residing at Bloomington, in the county of McLean and State of Illinois, have invented a new, original, and ornamental Design for Combined Washing Machine Casing and Wringer, of which the following is a specification, reference being had to the accompanying drawing, forming part thereof.

The figure is a perspective view of a combined washing machine casing and wringer showing my new design.

I claim:

The ornamental design for a combined washing machine casing and wringer, as shown.

In testimony whereof I have hereunto affixed my signature.

CHARLES K. WOODIN.
